UNITED STATES PATENT OFFICE.

BENJAMINE F. MOORE, OF PEEBLES, OHIO.

DUMPING-CAR.

No. 836,395.

Specification of Letters Patent.

Patented Nov. 20, 1906.

Application filed July 25, 1906. Serial No. 327,727.

To all whom it may concern:

Be it known that I, BENJAMINE F. MOORE, a citizen of the United States, residing at Peebles, in the county of Adams and State of Ohio, have invented certain new and useful 5 Improvements in Dumping -Cars, of which the following is a specification.

My invention relates to improvements in what may be termed "dumping-cars." Its 10 object is to provide for the ready and effective or satisfactory dumping action of the car, as well as its reverse manipulation to normal or loading position, and to accomplish these ends in a simple, economic, and 15 expeditious manner.

Said invention consists of certain structural features or instrumentalities, substantially as hereinafter fully disclosed and 20 specifically pointed out by the claims.

In the accompanying drawings, illustrating the preferred embodiment of my invention, Figure 1 is a perspective view of the same, showing the body or receptacle in tilted or dumping position. Fig. 2 is a longitudinal section taken centrally through the parts, with the body or receptacle in normal or upright position. Fig. 3 is a transverse section produced through the chain or cable winding shaft and its gear and through the 25 intergeared and chain or cable equipped shaft for tilting or dumping the car body or receptacle. Fig. 4 is a section produced longitudinally through one of the car-wheel axles equipped with the friction-coupling, 30 the clutch, and the sprocket-wheel for actuating the chain or cable for operating the chain or cable winding shaft aforesaid.

In carrying out my invention I suitably mount in position the body or hopper 1, preferably as shown, the central longitudinal or bottom bar or member 2 thereof, preferably of steel, having pivotal or hinge connections 3 with the central longitudinal draw-bar 4, fixed or bolted to the top of the car-frame 5 to permit the swinging or tilting of said car body or hopper laterally either way.

A longitudinal shaft 6, extending the entire length of the frame 5 and suitably journaled in position thereon, is intergeared by 50 the beveled gear-wheels 7 8 with a transverse shaft 9, likewise journaled in said frame, which shaft 6 is suitably equipped near its ends with winding-spools 10, around which are wound intermediate of their lengths 55 chains or cables 11, having their respective ends connected to the car body or hopper

upon opposite sides thereof at suitable points, as will be readily appreciated. Said chains or cables are passed into contact with and guided by pulleys 12, hung in suitable 60 brackets or hangers 13, secured to the under side of the longitudinal draw-bar 4. Suitable chains 15 or equivalents attached to the car-body and to the car-frame 5 serve to restrict the upward movement of said car-body 65 within required limits, as will be readily understood.

The shaft 9 has fixed thereto a sprocket-pinion 14, which is driven by an endless chain or belt 16, with which it is engaged, and 70 which belt or chain also engages and is itself driven by a sprocket-wheel 17, loosely arranged or carried upon a wheel-axle of the car for effecting the raising or restoring of the car body or hopper to normal or elevated 75 position after dumping its load, as will be clearly apparent later. Said sprocket-wheel 17 has projecting therefrom a slightly-tapered stub or extension 18, adapted to be slid frictionally tight or close within a correspondingly socketed hub-like casting 19, keyed or fixed upon said car-axle, these thus forming a friction-coupling.

A clutch 20 is suitably arranged upon the car-axle aforesaid for controlling said friction-coupling, comprising two members 21 85 22, interposed between the sprocket-wheel 17 and a collar 23, fixed to said axle, one having its arm 24 suitably connected to a fixed point—as for instance, the draw-bar 4—upon 90 its lower side, and the other clutch member having its arm 25 connected by a link 26 to a manually-actuated lever 27, suitably pivoted at its lower end to the end of the car-frame 5 and suitably controlled in its movement as it is actuated by a keeper or staple-like contrivance 28, through which it passes and which latter is secured to the car-frame. The clutch members 21 22 have upper and lower oppositely-inclined or spiral half 100 clutch-faces 29 29, opposed half clutch-faces of the two members having their corresponding inclinations facing each other. Accordingly the upper and lower half clutch-faces have their wider terminals presented upward and downward, respectively, whereby as said members are turned one against or upon the other said upward and downward presented terminals will finally serve as 110 stops for restricting or limiting the further movement of the actuated clutch member, during which movement of the latter, how-

ever, the sprocket-wheel, with its coupling stub or extension, will be forced requisitely along the car-axle to effect frictional engagement between said stub or extension and the 5 socket portion 19, fixed to said car-axle, thus providing for coupling these parts together. Said parts when thus coupled together provide, it is obvious, for utilizing the action of the car-axle for winding the car body or hopper 10 actuating chains or cables upon the spools of the shaft 6 in returning said car body or hopper to its normal or upright position after having been tilted or dumped in discharging its contents. The half clutch-faces 29 of each clutch member are bolted 15 together in any suitable way, preferably as shown.

I claim—

1. A dump-car employing a pivoted or 20 tilting body portion or hopper, a chain or cable winding shaft for actuating said hopper or body portion and a transverse shaft driven from a car-axle, said shafts being intergeared.
2. A dump-car employing a pivoted or 25 tilting body portion or hopper, a chain or cable winding shaft for actuating said body portion, a transverse shaft having a sprocket-pinion, a car-axle having a sprocket-wheel

thereon, an endless driving-belt engaging 30 said sprocket-pinion and sprocket-wheel, said shafts being intergeared, and means for effecting the slipping of said sprocket-wheel into operative engagement with said car-axle.

3. A dump-car employing a pivoted or 35 tilting body portion or hopper, means for actuating said body portion or hopper, a coupling between a car-axle and said car-body-actuating means, and a clutch device arranged upon said car-axle, comprising two members having arms one connected to a fixed point and the other arm having connected thereto actuating means, said clutch members having upper and lower oppositely- 40 inclined or spiral half-faces, with corresponding half-faces opposed to each other and upward and downward presented terminals of 45 said half-faces effective for mutual engagement.

In testimony whereof I have signed my name to this specification in the presence of two subscribing witnesses.

BENJAMINE F. MOORE.
